UNITED STATES PATENT OFFICE

CHRISTIAN F. ROUTHE, OF REDWOOD FALLS, MINNESOTA

CONVEYER FOR GRAIN BINDERS

Application filed December 16, 1929. Serial No. 414,528.

This invention relates to canvas conveyers for grain binders and is applicable to such conveyers whether of the apron type or elevator type.

An objectionable feature of such conveyers is that the canvas will shrink when moist as when wet grain is being handled, and will expand when dry, thereby causing too much or too little tension on the conveyer rollers. An object of the present invention therefore resides in the provision of an automatic tension device which will allow for shrinkage of the canvas, and which will take up the slack when the canvas dries out.

A further object of the invention consists in the provision of such a device which is free from liability to interfere with the passage of the canvas over the conveyer rollers.

Another object of the invention consists in the provision of a tension device which is readily adapted to conveyers of different widths.

Still another object of the invention consists in providing a tension device which is strong and durable in operation and which may be applied to the conventional canvas conveyers in general use.

Other objects and advantages of the invention will be apparent from the following description when taken in connection with the accompanying drawings, in which

Figure 1 is a plan view of a conveyer with the novel tension device incorporated therein, parts being broken away to more clearly disclose the construction.

Figure 2 is a side elevational view of the conveyer and tension device.

Figure 3 is a fragmentary detail view of the tension device.

Figure 4 is a vertical sectional view through the tension device and related parts.

Figure 5 is a horizontal sectional view through the spring-containing tube of the tightener or tension device; and

Figure 6 is a perspective view of the tube partly broken away.

Referring to the drawings in greater detail the numeral 1 indicates a pair of spaced rollers of conventional type over which extends a belt 2 usually formed of canvas and provided with transverse slats 3. This is the usual construction of conveyers commonly known as the apron canvas for conveying the grain transversely of the direction of movement of the binder to the binding apparatus, and for carrying away the tied bundles of grain.

These canvases quite often become damp in the early morning by reason of the apparatus handling grain moistened by dew or the like, and later on in the day become dried out. These different conditions, of course, cause a contraction and expansion of the conveyer belt and considerable difficulties are caused by reason of the sagging of the belt or the too tight binding of the belt on the rollers. To overcome these difficulties I have provided the present construction of tensioning device or tightener for connecting together, in an expandible manner, the ends of the belt 2.

In the present embodiment of the invention a metal tube 4 is provided which is secured to one end of the belt 2 and extends transversely thereof, as indicated in Figure 1. This tube forms an inclosure and anchoring means for a plurality of tension springs 5, four of these springs being shown in the present instance. These springs have one end thereof anchored to the interior of the tube by means of bolts 6. Two of the springs extend toward one end of the tube from their anchoring means, and the other two springs extend toward the opposite end thereof. The outer ends of the springs are connected to flexible members 7, preferably leather straps, which are threaded through the ends of the respective springs and are doubled upon themselves, as indicated in

Figure 5. These straps are passed over the guide bearings 8 and extend outwardly of the tube 4 through slots 9 and are provided with buckles 10 by means of which the straps are detachably connected to straps 11 which are anchored to the opposite end of the belt. By this means it will be apparent that any contraction of the canvas or other material of which the belt conveyer is made, will be allowed for through the extension of the springs 5 longitudinally of the tube and transversely of the belt. Likewise, as the material of the belt expands the springs 5 will contract, thereby maintaining a substantially uniform tension or binding action over the rollers 1.

In order that access may be conveniently had to the interior of the tube 4 for repairing broken springs or straps, slits 12 are provided in the metal of the tube at about the point of connection between the springs and straps. By means of these slits the metal outlined by the slits may be bent up when desired as indicated in Figure 6, thus permitting access to the interior of the tube.

The width of canvas or other material used in these belt conveyers sometimes varies and in order that the tube 4 may be used with different widths of canvas, the same is made extensible by the use of plugs 13 preferably of wood. These plugs are provided with a plurality of perforations 14 through the medium of which and the bolts 15, the plugs may be locked in their innermost position as shown in Figure 5, or in an intermediate position as indicated in Figure 3, thus rendering the length of the tube adjustable to conform to varying widths of canvas employed in the conveyer.

Due to the fact that the force applied to the strap 7 is at a distance somewhat above the base of the tube 4, it will be apparent that there is a tendency for the tube to tilt forward and thus tear out the rivets 16 by which the tube is attached to the belt, and in order to prevent this tilting action and thereby eliminate this difficulty, springs 17 are provided. These springs are anchored to the tube 4 at a point adjacent the top thereof, as by means of the rods 18, and the opposite ends of the springs are anchored to the adjacent slat 19 of the conveyer by means of the rods 20. It will thus appear that these springs provide a downward pull on what may be termed the rear end or side of the tube 4, and thus serve to hold the same down against the canvas and prevent the pulling out of the rivets 16.

It is desirable, of course, to cover the connecting straps 7 and 11 and the buckles 10, as well as the springs 17, so as to prevent interference of these elements with the material being handled by the conveyer, and for this purpose one of the ends 21 of the belt extends beyond the connecting means

and overlaps tube 4 and spring 17 with sufficient margin to maintain a covering for these elements even when the belt is contracted to its greatest extent.

The operation and general arrangement of belts of this type is well understood and need not be described herein except to say that with the present novel arrangement by which an elastic connection is made between the ends of the belt, the action of the conveyer is greatly improved due to the fact that expansion and contraction of the belt body is automatically taken care of by the tension device, and that the construction by which this end is attained is so designed as to prevent any interference in the passage of the conveyer or belt over the rollers. It will also be apparent that the tensioning device as shown and described is adaptable to use with conveyer of varying widths by reason of the adjustable length of the tube 4, and that means are provided for permitting ready access to the interior of the tube for the purpose of repair of the operating parts.

In accordance with the patent statutes I have described what I now believe to be the preferred form of construction, but inasmuch as various minor changes may be made in the details of construction, it is intended that such changes be included within the scope of the appended claims.

What I claim as new and desire to secure by Letters Patent is:

1. A tightening means for a conveyer belt, said means including a tube secured transversely of one end of the belt, a spring in said tube, and flexible means having one end connected to said spring and the other end connected to the opposite end of said belt. 100

2. A tightening means for a conveyer belt, said means including a tube secured transversely of one end of the belt, a spring in said tube, flexible means having one end connected to said spring and the other end connected to the opposite end of said belt, and extensible members mounted in the ends of said tube. 110

3. A tightening means for a conveyer belt, said means including a tube secured to the belt transversely of one end thereof, a spring in said tube, means for connecting an end of said spring to the other end of the belt, and elastic means for preventing the tilting of said tube. 115

4. A tightening means for a conveyer belt, said means including a tube secured transversely of one end of the belt, a spring in said tube, means for connecting an end of said spring with the other end of said belt, a slat secured transversely of the belt and spaced from said tube, and coil springs having their respective ends secured adjacent the top of said tube and adjacent the bottom of said slat. 125

5. In a conveyer, a tightening element including a metal tube, coil springs in said tube, means for anchoring one end of each of said springs to the tube, flexible means
5 attached to the other ends of said springs and adapted to be connected to the conveyer, said tube provided with slits adjacent the connections between the springs and flexible means, whereby the metal between said slits
10 may be bent upwardly to afford access to the interior of the tube.
